UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS SONS & MAXIM, LIMITED, OF WESTMINSTER, LONDON, ENGLAND.

CARTRIDGE-EXTRACTOR FOR GUNS.

SPECIFICATION forming part of Letters Patent No. 708,871, dated September 9, 1902.

Application filed February 28, 1902. Serial No. 96,152. (No model.)

To all whom it may concern:

Be it known that we, ARTHUR TREVOR DAWSON, late lieutenant of Royal Navy, and GEORGE THOMAS BUCKHAM, engineer, subjects of the King of Great Britain, both residing at 32 Victoria street, Westminster, in the county of London, England, have invented certain new and useful Improvements in Cartridge-Extractors for Guns, of which the following is a specification.

This invention has reference to cartridge-extractors for breech-loading guns of the kind in which the block is mounted in a swinging carrier.

One of the objects of the invention is to so construct and arrange the said extractor that it will exert first a powerful rearward pull or prizing action on the rim or flange of the cartridge-case, and then just before the breech is fully opened will strike the rim or flange a sudden blow to eject the cartridge-case from the breech-chamber.

We will describe our invention with reference to the accompanying drawings, in which—

Figure 1 is a horizontal section of a portion of the breech end of a gun provided with our improved extractor. Fig. 2 is an elevation, and Fig. 3 a plan, of the said extractor removed from the gun.

A is the wall of the breech-chamber of the gun.

B is the swinging carrier, on which the breech-block is mounted in any usual or appropriate manner, and B' is the hinge-pin, about which said carrier swings.

C is the cartridge-case.

D is the extractor, which is mounted to oscillate on a vertical pin or pivot a, carried by the gun. Said extractor comprises a lever with three arms, two of which—viz., d d—

form a U-shaped piece to lie concentric with the cartridge-case, while the other arm—viz., d'—extends from the base or bottom of the U-shaped piece and projects through an opening a' in the wall of the breech-chamber. This arm d' is bent to form a tail d'', whose end lies contiguous to the hinge of the swinging carrier, which is formed with a cam-surface b for acting upon said tail when the carrier is

being swung open. The ends of the aforesaid U-shaped arms d d have lips d², which are suitably shaped to lie in front of and engage with diametrically opposite sides of the rim or flange of the cartridge-case, Fig. 1. These lips we term for sake of distinction “ejecting-lips.” At the base or bottom of the U-shaped arms of the extractor is another lip d³, which we term for sake of distinction an “extracting” or “prizing” lip. This prizing-lip lies in front of and engages with the rim or flange of the cartridge-case in a position substantially at right angles to an imaginary line extending through the two ejecting-lips d², Fig. 1. These ejecting-lips are so formed that a small space exists between them and the flange or base of the cartridge-case when the extractor is fully home or in the position represented in Fig. 1. As the carrier is swung open the cam-surface b thereof acts upon the tail d'', whereby the extractor is caused to move in an outward direction. This movement, which is at first comparatively slow, causes the prizing or extracting lip d³ to exert a powerful rearward pull or prizing action upon the cartridge-case to liberate it from the breech-chamber. Then as a depression or shoulder b' of the said cam-surface b engages with the tail d'', said extractor receives a sudden accelerated movement, which causes the ejecting-lips d² to strike a sharp blow upon the rim or flange of the cartridge-case, whereby the latter, which has been previously loosened by the prizing-lip d³, is promptly ejected from the breech-chamber.

Obviously in some cases the said extractor may be furnished with only one arm d instead of two such arms, as illustrated.

What we claim, and desire to secure by Letters Patent of the United States, is—

1. The combination with the swinging carrier of a breech-loading gun, of an extractor consisting of a pivoted lever having lips adapted to engage with the flange of the cartridge-case, first at a point in proximity to the pivot of said lever and then at a point remote from said pivot, and of means for actuating said lever during the swinging of the carrier, substantially as described.

2. The combination with the swinging car-

rier of a breech-loading gun, of an extractor consisting of a U-shaped pivoted lever having ejecting-lips at its inner ends an extracting or prizing lip at the base of the U and 5 also having a tail projecting through an opening in the breech-chamber and lying in the path of a cam-surface on the carrier-hinge substantially as and for the purpose described.

- 10 3. The combination with the swinging carrier of a breech-loading gun, of an extractor consisting of a U-shaped pivoted lever having at its inner ends ejecting-lips which lie a short distance in front of the cartridge-flange 15 when the breech is closed, an extracting or prizing lip at the base of the U to lie in close contact with the front of the cartridge-flange

at the side nearest to the pivot of the extractor, and a bent tail projecting through an opening in the breech-chamber and lying close to a cam-surface on the carrier-hinge, said cam-surface being formed with a shoulder for imparting to the extractor a sudden accelerated movement during the completion of the opening movement of the carrier substantially as and for the purpose specified. 25

In testimony whereof we have hereunto set our hands, in presence of two subscribing witnesses, this 19th day of February, 1902.

ARTHUR TREVOR DAWSON.
GEORGE THOMAS BUCKHAM.
